TUBE CHAMFERING TOOL

Frank G. Brown, Silver Lake, South Lyon, Mich.

Application March 28, 1938, Serial No. 198,455

11 Claims.

(Cl. 77—73)

This invention relates to chamfering tools, and particularly tools for chamfering tubes, rods, or tubular openings.

An object of the invention is to provide a chamfering tool, which will cut to a depth determined by the pressure under which the tool is engaged with the work.

Another object is to provide a chamfering tool, the cutter of which may be adjusted to predetermine the maximum depth of cut.

A further object is to provide a chamfering tool, which will be accurately self-centering and will be adapted to produce annular chamfers of widely varying diameters.

These and various other objects are attained by the construction hereinafter described and illustrated in the accompanying drawing, wherein:

Fig. 1 is a top plan view of the tool as designed to produce interior annular chamfers, the parts being disposed to establish a non-cutting position of the blade.

Fig. 2 is an end view of the same.

Fig. 3 is a side elevational view of the same, showing the parts disposed to position the blade for a maximum cut.

Fig. 4 is a sectional view of the tool, taken on the line 4—4 of Fig. 3.

Fig. 5 is a perspective view of the cutting blade and a head carrying the same.

In these views, the reference character 1 designates a disk-shaped head, splined or otherwise fixed upon a shaft comprising portions 2 and 3, respectively projecting rearwardly and forwardly from said head. The portion 2 serves as a shank, engageable with any suitable driving member,

not shown. The portion 3, which is preferably of lesser diameter, slidably mounts a conical, blade driving and guarding pilot member 4 formed with an axial, forwardly extending blind

socket 5 to receive the shaft. The angle formed between the axis and coned face of the member 4 is predeterminedly equal to the angle of the chamfer which the tool is designed to produce. The head 1 is radially grooved to snugly accommodate the rear end portion of a cutting blade

6, rigidly secured in said groove by a set screw 7. The blade projects forwardly from the head substantially to the front end of the pilot member, slidably fitting in a radial groove extending from end to end of such member. The cutting edge

6a of the blade is converged toward the axis of the tool at the same angle as the conical face of the pilot member, said edge being substantially flush with the coned face of said member when the head 1 and blade are retracted as in Figs. 1

and 2, and predeterminedly projecting beyond such face when the head and pilot member are abutting, as in Figs. 3 and 4. A drive-transmitting lug 8 rearwardly projecting from the pilot member has a sliding fit in a radial groove 9

peripherally opening in the head 1, said groove being preferably diametrically opposed to that accommodating the blade. A screw 10 tapped into the lug 8 has a head seating against the rear face of such lug and laterally projecting beyond the latter to act as a stop engageable with the rear face of the head 1 to limit separative travel of the head and pilot member. A plurality of coiled springs 11 set into sockets 12 of the pilot member exert a thrust on the head 1 tending to maintain a maximum retraction of the head and blade, with respect to the pilot member, as per Fig. 1. At one side of the blade, and in proximity to its cutting edge, the pilot member is cut away from end to end thereof, as indicated at 13, to afford adequate clearance for cuttings. In Fig. 3 there is sectionally shown at 14 a tube positioned to receive a chamfering cut.

In use of the described tool, the shank 2 is engaged by any suitable rotatable driving member, which may be either power driven or manually actuatable. The pilot member is engaged in the opening of a tube or other opening, abutting the edge to be chamfered. While being rotatively driven, the tool is subjected to a gradual forward feed. Since the pilot member cannot respond to such feed, being restrained by the work, the head 1 moves forward, compressing the springs 11 and advancing the blade. Such advance effects a projection of the cutting edge beyond the coned face of the pilot member, and renders such edge effective on the work. Obviously, a heavy or a light cut may be taken according to the forward pressure applied at the shank 2. The maximum cut is achieved when the head 1 is abutted against the pilot member. In case it is desired either to increase this maximum or compensate for wear of the cutting edge 6a, the set screw 7 may be loosened and again tightened after shifting the blade suitably forward.

As compared to prior tools for a like purpose, the described construction presents various advantages. Controlling the depth of cut by merely regulating the applied forward pressure, eliminates necessity for adjustment in adapting the tool to metals or other materials of different hardness. In correspondingly chamfering a quantity of similar tubes, the advance of the head 2 with respect to the pilot member may serve to indicate completion of a desired chamfer, and the blade may be initially set so that abutment of the head 2 against the pilot member will indicate a completed chamfer. When not in use, the blade is so withdrawn into the pilot member as to protect it against rough usage. Reaction of the blade to a cutting operation is transmitted to the pilot member in such proximity to the cutting edge as to minimize stresses in the blade and eliminate any chattering or vibration of the blade. In other words, the pilot

member applies a drive to the blade substantially throughout the blade length and in close proximity to the cutting edge.

5 While the illustrated tool is equipped with a single blade, it is obvious that a plurality of blades might be provided, without change of principle. It is further evident that a pilot member having an interiorly coned surface may be equipped with a blade adapted to project beyond such surface for producing an exterior annular chamfer, just as an interior chamfer is produced by the described tool.

10 The invention is presented as including all such modifications and changes as come within the scope of the following claims.

15 What I claim is:

1. A rotary chamfering tool comprising a blade having a cutting edge converged forwardly substantially toward the axis of the tool at the desired angle of chamfer, a driving member for the blade, having a work-abutting surface converged toward said axis in substantially the same angular relation thereto as the cutting edge of the blade, the blade being slidable on such driving member along said axis to variably expose the cutting edge beyond said surface, means yieldably urging the blade rearwardly to a position minimizing exposure of the blade, and an element transmitting a drive to the blade-driving member and effective on the blade to advance it forwardly on the blade-driving member and effect a desired exposure of its cutting edge.

2. A rotary chamfering tool comprising a head adapted to be rotatively driven, a cutter secured to such head and projecting therefrom substantially along the axis of rotation of the tool, said cutter having a cutting edge converged substantially toward said axis at a desired angle of chamfer, a pilot and driving member for the blade carried by and slidable to and from said head and forming a guard for said cutting edge, and adapted to increase or diminish the effective exposure of such edge according as it is slid toward or from the head, means yieldably urging the head and pilot member separatively, and means limiting separative travel of the head and pilot member.

3. A chamfering tool as set forth in claim 2, said pilot member being of a substantially conical form, its angularity to the tool axis substantially equalizing that of said cutting edge to such axis.

4. In a chamfering tool as set forth in claim 2, means securing the cutter to said head, adapting the cutter to be adjusted to vary the extent of its projection from the head.

5. In a chamfering tool as set forth in claim 2, a member projecting from said head along the axis of the tool and slidably mounting the pilot member.

6. In a chamfering tool as set forth in claim 2, a member disposed at the axis of the tool and slidably mounting the pilot member on said head, and a lug projecting substantially in the direction of sliding travel of the pilot member, establishing a rotary drive from the head to the pilot member and rigidly carried by one thereof and slidably engaging the other.

7. A chamfering tool as set forth in claim 2, a lug establishing a rotary drive from the head to the pilot member rigidly projecting from one thereof in the direction of sliding travel of the pilot member and slidably engaging the other,

said limiting means being carried by such lug.

8. A rotary chamfering tool comprising a head adapted to be rotatively driven, a cutter secured to such head and projecting therefrom substantially along the axis of rotation of the tool, said cutter having a cutting edge converged substantially toward said axis at a desired angle of chamfer, a pilot member for the tool forming also a guard for said cutting edge, an element mounting the pilot member on the head rigidly carried by one thereof and slidably engaging the other, said element being disposed at the axis of the tool, a member establishing a drive from said head to the pilot member, rigidly carried by the outer portion of the pilot member and slidably engaging the head, means carried by the last named member limiting separative travel of the head and pilot member, and means yieldably urging the pilot member and head separatively.

9. A rotary chamfering tool comprising an approximately conical pilot member, having its apex forming the front end of the tool, a cutter set into said pilot member, with its cutting edge converged substantially toward the axis of the tool at substantially the same angle as the conical face of the pilot member, a head disposed rearwardly of the pilot member, and adapted to be rotatively driven, means securing the rear end portion of the cutter to such head, a forward projection on the head at the tool axis slidably mounting the pilot member for movement to and from the head, a lug rigidly carried by and rearwardly projecting from the pilot member and slidably fitted in the head to establish a rotary drive from the head to the pilot member, means carried by such lug for limiting separative travel of the head and pilot member, and spring means reacting between the head and pilot member and urging them separatively.

10. A rotary chamfering tool comprising a head adapted to be rotatively driven, a cutter mounted on such head and projecting forwardly therefrom and having a cutting edge converged substantially toward such axis at a desired angle of chamfer, a driving member for the cutter carried by and slidable to and from the head and forming a guard for said cutting edge and adapted to increase or diminish the effective exposure of such edge according as it is slid toward or from the head, means yieldably urging the head and driving member separatively, means limiting separative travel of the head and driving member, and means securing the blade to the head affording the blade a forward adjustment on the head.

11. A rotary chamfering tool comprising a head adapted to be rotatively driven, a blade secured to such head and projecting forwardly therefrom, a driving member for the blade mounted forwardly of the head, the blade having a cutting edge converged substantially toward the axis of rotation of the tool, and the driving member having a surface adjacent said edge correspondingly converged, means supporting the driving member on the head, affording such member sliding travel to and from the head, means for transmitting a drive to the driving member in all positions of such sliding travel, spring means interposed between the head and driving member urging the driving member forwardly, and means limiting travel of the driving member forwardly from the head.

FRANK G. BROWN.
